BY Malton B. Moulton
ATTORNEY

UNITED STATES PATENT OFFICE.

WILLIAM L. McGEE, OF MEDIA, PENNSYLVANIA.

DESIGN FOR A COMBINED CASING FOR A FLOOR-POLISHING BRUSH AND HANDLE THEREFOR.

Application filed June 22, 1928. Serial No. 27,230. Term of patent 14 years.

To all whom it may concern:

Be it known that I, WILLIAM L. McGEE, a citizen of the United States, and a resident of the borough of Media, in the county of Delaware and State of Pennsylvania, have invented a new, original, and ornamental Design for a Combined Casing for a Floor-Polishing Brush and Handle Therefor, of which the following is a specification, reference being had to the accompanying drawing, forming a part thereof.

Fig. 1 is a right hand side elevational view of a combined casing for a floor polishing brush and handle therefor, showing my new design.

Fig. 2 is a plan view of the said casing on a larger scale than that of Fig. 1, with all of the handle, except the yoke, removed.

Fig. 3 is a front elevational view of the casing with the yoke and a fragmentary part of the handle attached thereto.

Fig. 4 is an elevational view of the left hand side of the casing and with said yoke and a fragmentary part of the handle attached thereto; and

Fig. 5 is a rear elevational view of said casing with said yoke and a fragmentary part of the handle.

I claim:

The ornamental design for a combined casing for a floor polishing brush and handle therefor, as shown and described.

WILLIAM L. McGEE.
